OF HOPEDALE, MASSACHUSETTS, A CORPORATION OF MAINE.

LOOM FILLING-STAND.

03 1,082,186.

Specification of Letters Patent. Patented Dec. 23, 1913.

Application filed August 3, 1912. Serial No. 713,134.

To all whom it may concern:
Be it known that I, FRANCIS E. ASHTON,
a citizen of the United States, residing at
Exeter, in the county of Rockingham and
5 State of New Hampshire, have invented an
Improvement in Loom Filling-Stands, of
which the following description, in connec-
tion with the accompanying drawings, is a
specification, like characters on the drawings
10 representing like parts.

The invention to be hereinafter described
relates to loom filling stands, whereby the
ends of the filling wound on the filling car-
riers may be readily found and presented to
15 the weaver.

As well known by those skilled in the art,
at the conclusion of the spinning and wind-
ing operations incidental to the preparation
of yarn for use as filling during the weaving
20 of cloth, the end of the yarn is usually left
clinging closely to the body of the yarn
or wound on the carrier. In looms of the filling
replenishing or so-called automatic type,
however, the filling carriers are placed in a
25 battery or hopper and it is necessary to se-
cure the ends of the filling so that, when a
carrier is transferred to the shuttle, filling
will be laid in the shed on the first pick of
the shuttle. Owing to the fact that the ends
30 of the filling cling to the body of the filling
as above-noted, much difficulty is ex-
perienced and much time lost by the weaver in
finding the filling end and unwinding the
same to lead the filling from the smaller end
35 of the carrier.

With these facts in mind, the aims and
purposes of the present invention are to pro-
vide means whereby, preparatory to placing
the filling carriers in the battery or hopper,
40 the filling ends may be readily found and
presented to the weaver, and while the in-
vention is thus more especially of value in
connection with filling replenishing or auto-
matic looms, it is nevertheless adapted for
45 use in any condition which renders it de-
sirable to find and present the filling end
to the weaver, as for instance in threading
a shuttle, all of which will best be made
clear from the following description and
50 accompanying drawings of one convenient
form of means for carrying the invention
into practical effect, it being understood that
in its true scope the invention is defined by
the claims.

55 In the drawings:—Figure 1 is a side ele-

vation of a filling stand embodying the
present invention, some of the parts being
shown broken away; Fig. 2 is an enlarged
sectional view, as on the line 2—2, Fig. 1,
with the carrying slide partially raised to
show the action of the brushes and rotating
devices on the filling and carrier; Fig. 3 is
a detached view of the carrying slide; Fig. 4
is an enlarged detail in section showing how
the filling carrier and its load is treated as
the carrier is moved by the carrying slide;
and Fig. 5 is a detail view of the bottom of
the hopper or box at its discharge portion.

In its broad sense the invention contem-
pates means for acting upon the body of
filling wound upon the carrier and by rela-
tive movement of such means and the filling
carrier to find and temporarily hold the end
of the filling wound thereon; and, in the
form of the invention herein shown, the
carriers appropriately supplied with filling
and in desired number, are delivered to a
carrying frame by which they may be moved
relative to and into contact with filling end
finders to which the filling ends adhere, as
will now be described.

The frame for sustaining the various parts
may be of any appropriate character, such
as for instance, as the base 1, from which rise
the side frames 2 and 3 supporting a rest or
table 4 preferably, though not necessarily in-
clined, as shown by Fig. 1, and adapted to
removably sustain a hopper or box 5. The
hopper or box 5 may be of any desired char-
acter, for containing a series of filling car-
riers 9 having a supply of filling wound
thereon, and is provided with a discharge
opening 7, Fig. 5, through which the filling
carriers may pass singly, as indicated in
Fig. 1. The hopper or box 5 is preferably
of a width between its sides 8, 8, Fig. 2, ap-
proximately equal to the length of the filling
carriers or bobbins 9, so that the filling car-
riers may be arranged in said hopper in an
orderly manner, with their lengths extend-
ing widthwise of the hopper, as indicated by
Fig. 1.

The discharge opening 7 at the bottom of
the hopper is normally closed when the
hopper is not upon the table or rest 4, and
as one form of means for so closing said
opening, the bottom of the hopper 5 is pro-
vided with a gate or slide 10, preferably of
the general form shown, and normally under
the influence of a spring 11 for holding the

gate or slide in close position. As hereinbefore noted, the hopper or box 5 is preferably removable from the rest or table, though this may not be regarded as an essential, but rather as a convenient arrangement to enable the hopper or box to be taken to the spinning frames, where the filling carriers may be placed in the hoppers directly by the operatives as they doff the said frames. However, other arrangements may be conveniently employed and the filling carriers can be taken to the filling stand and there placed in the hopper. When the former expedient is practiced it is desirable that the gate or slide 10 be automatically opened to permit filling carriers to pass, when the hopper is placed in position on the table or rest 4, and as one form of means to this end the gate or slide 10 may be provided with a projection 12 to engage a shoulder or stop 13 on the table or rest 4 as the hopper is moved endwise to place on said table or rest substantially as indicated in Fig. 1. If desired, the table or rest 4 may be provided with side guides 14 to guide or direct the hopper 5 to its proper position when moved endwise on said table or rest.

Mounted for sliding movement between the side pieces 3, 3, Figs. 1 and 3, of the main frame, is the filling carrier frame, which may be of an appropriate character to receive and support filling carriers having filling wound thereon. In the particular form of the carrier frame shown, it comprises suitable side pieces 15 and 16 provided with rests 17 and 18 respectively adapted to engage and hold the filling carriers adjacent the tip and base portions thereof. It will be noted that the rests 17 and 18 have upwardly extended entrance passages, so that filling carriers may be readily placed in and taken from the carrier frame; and that the rests 17 are somewhat larger and deeper than the rests 18 in order that the former may engage and accommodate the base portions of the filling carriers and that the latter may properly support the filling carriers near the tip portions, thus holding the carriers in proper alignment transversely of the carrier frame.

The side pieces 15 and 16 of the carrier frame may be appropriately joined together at their lower portions by the cross-pieces 19 and 20, and may be further braced at intermediate points by tie rods 21, preferably disposed below the rests 17 and 18 in order that when the frame is raised and the weaver wishes to remove the filling carriers from the frame it may be done readily and without unnecessary obstruction to the hand movement.

The side pieces 3, 3 of the main frame are connected together at the front and rear by the front and rear members 22 and 23 respectively, thus forming a substantially box-

like guide for the filling carrier frame as it is moved up and down in the main frame, as will presently appear, though obviously other forms of guiding means might be employed and will suggest themselves to those skilled in the art.

As hereinbefore noted, the filling carrier frame is adapted to be moved up and down in suitable guides formed by the parts described, and any desired character of means for giving the filling carrier slide this movement may be employed, but a good, practical form of such means is shown by Fig. 1, wherein the side frames 2 and 3 have extending between them a support 24 carrying suitable bearings for a shaft 25 on which is secured a wheel 26 connected by a strap or other flexible device 27 with a treadle 28 pivoted at 29 at the base of the supporting frame. Likewise secured to the shaft 25 is the larger wheel 30 connected by the strap or other flexible connection 31 to the lower portion of the filling carrier frame as at 32, Figs. 1 and 3, the construction being such that upon depression of the treadle the shaft 25 will be rotated clockwise and through the described connections 30 and 31 with the filling carrier frame, such frame will be given a rising movement in its guides. The construction is such that a small movement of the treadle imparts sufficient movement to the filling carrier frame to move it from its lower to its extreme upper position, as will be hereinafter described, in which latter position the rests 17 and 18 supporting the filling carriers will be exposed in convenient position for removal of the carriers therefrom by the weaver.

In order that the filling carriers 9 contained within the hopper 5 may be properly fed to the filling carrier frame, the table or rest 4 and the rear wall 23 of the guiding frame are provided respectively with passageways connected by a chute 33, Fig. 1, the construction being such that when the hopper 5 is placed upon the rest or table 4, and its gate or slide is opened, either in the manner stated or otherwise, the filling carriers contained within the hopper may be freed to pass singly from the hopper through the chute 33 into the filling carrier frame. When in its lowest position, the filling carrier frame may, if desired, present the upper one of the rests 17 and 18 opposite the chute 33, under which conditions, as soon as the gate or slide of the hopper is opened, the first filling carrier to pass therefrom will travel down the chute and find its ultimate position in the rests 17 and 18 of the filling carrier frame, the filling carrier 9 at such times preferably bearing at its base portion 34, Fig. 2, in the enlarged rests 17 and by its tip portion 35, Fig. 2, in the smaller rests 18. Upon depression of the treadle the rests 17 and 18 are brought successively opposite

the opening in the chute and as they travel past such opening, a filling carrier drops into said rests and finds its final position as did the first-mentioned carrier, until all of the rests in the filling carrier frame are supplied with filling carriers.

In the particular device illustrated as the present embodiment of the invention, the filling carrier frame is shown as provided with a series of four rests for filling carriers, but it is obvious that any appropriate or desired number of rests may be employed. As the filling carrier frame rises under action of the treadle and continues to rise after the rests 17 and 18, regardless of their number, have been supplied with filling carriers, the filling carrier at the end of the chute is retained in such position by having its end portions bear upon the surfaces 36 and 37 of the side pieces 15 and 16 of the filling carrier frame, so that as the filling carrier frame continues to rise after it has been charged with filling carriers, it serves also to hold back the remaining filling carriers in the chute until the filling carrier frame is subsequently brought to charging position.

As hereinbefore noted, the ends of the filling wound upon the carriers cling closely to the body of the filling at some point, and it is desirable that the ends of the various filling carriers before they are placed in the battery or hopper of a loom, shall be presented to the weaver in order that he may fasten them for reasons hereinbefore noted, and it is likewise desirable that the filling when placed in the battery or hopper shall lead from the smaller end or delivery portion of the filling carrier and with these facts in view the present invention in the form illustrated contemplates means for engaging the surface of the wound filling on the carriers as such carriers are moved upward by the filling carrier frame, whereby the end of the filling is found and held while the carrier from which it is detached moves upward to final position, and as such means constitute a filling end finder, it will, hereafter, be designated as a filling end finder.

As one form of filling end finder, the boxlike portion of the framing in which the filling carrier travels is extended upward above the table or rest 4 and has the front wall 22 thereof provided with a series of brushes 38, Figs. 1, 2 and 4, which are sufficiently extended from the wall 22 to engage the body of the filling wound upon the carriers as the carriers move past such brushes with the result that the brushes 38 will engage and hold the end of the filling on the carriers, so that when the filling carrier frame has been moved to its extreme upward position and the filling carriers supported thereby have been moved into dotted line position, Fig. 1, where they can be grasped by the hand of the weaver,

the ends of the filling of the respective carriers will still be held by the filling end finder or brushes and be in convenient position to be readily reached by the weaver.

While a series of brushes 38 extending throughout the length of the upper portion of the guide for the filling carrier frame have been illustrated as a good, practical and convenient form of filling end finder, it is to be understood that any suitable means which may engage and act upon the body of the filling on the carrier as said means and filling carrier are relatively moved, is contemplated within the spirit of the present invention.

It is sometimes desirable to rotate the filling carriers as they are being treated by the filling end finder in order that the final winds of filling placed upon the carrier at the conclusion of the spinning operation may be unwound therefrom and thus allow the filling end finder to hold the end of the filling as the filling carriers move relatively thereto. This is particularly desirable where at the conclusion of the spinning operation the end of the filling has been wound one or more times about the body of the filling carrier near the base portion thereof, because by so rotating such wound filling carrier, the end of the filling will finally lead from the smaller or delivery end portion of the filling carrier, when such carrier has been moved by the carrier frame to its uppermost position, as will be readily understood. As a convenient form of means for thus causing the filling carriers to rotate as they are moved past the filling end finder, the present invention contemplates means to act frictionally upon the body of the filling as the filling carrier moves past the filling end finder, and as one convenient form of such means, the present invention shows a series of teeth 39, Figs. 1, 2 and 4, projecting from the upper portion of the rear wall 23 of the guideway in which the filling carrier frame moves. These teeth or rotating devices project toward the filling end finder on the opposite wall and are adapted to engage the body of the filling on the filling carrier substantially as indicated in Fig. 4, so that as the filling carriers move past the filling end finder and the rotating devices 38 and 39 respectively, the filling carrier and its load will be appropriately rotated to enable the filling end finder 38 to hold the end of the filling as the filling carriers are moved upward and finally reach their uppermost position.

It will be noted that the filling end finder and the rotating devices 38 and 39 respectively extend substantially the full length of the cylindrical portion of the body of filling wound upon the carrier, see Fig. 2, so that both the filling end finder and the

rotating devices act with non-injurious effect upon the body of the filling and the filling end finder is adapted to find the end of the filling regardless of its position with

5 relation to the body of the wound filling. Obviously the filling end finder or brushes 38 may extend the full length of the wound portion of the filling carrier, but if desired only may they extend along the cylindrical 10 portion of the filling carrier, but if desired may extend to the end portion thereof, substantially as indicated by dotted lines in Fig. 2, so that no matter where the end of the filling may have been left at the conclusion 15 of the spinning operation, the filling end finder will unerringly find and hold it.

While the teeth or abutments 39 have been found to be a good, practical form of rotating device for the filling carriers, it will be 20 understood that any appropriate means may be employed to rotate the filling carriers as they move past the filling end finder, the essential in this regard being that the filling carriers be thus rotated in order that 25 the ends of the filling which are found by the filling end finder shall be retained by the finder as the filling carriers are moved to their uppermost position.

By reference to Fig. 2, and as indicated by 30 the arrows therein, it will be seen that rotating the filling carriers acts upon the filling carriers to give them rotation in a direction opposite to the direction of wind by which the filling was placed upon the carrier so that upon rotation of the filling carriers by said rotating means, the ends of the filling will be unwound from the carriers.

From the construction described it will be apparent that when the filling carrier frame 40 has been moved upward to its extreme limit, the filling carriers supported by it will have been moved past the filling end finder and the rotating devices will have acted, so that the ends of the filling will project downward 45 from the carriers and be held by the filling end finder, with the result that the weaver may by one hand detach the series of filling carriers from the carrier frame and with his other hand may manipulate the 50 ends of the filling and readily attach them to the desired part when he places the filling carriers in the hopper or battery of the loom.

A filling carrier stand containing the essentials of the present invention may be attached to or form part of each loom, or it 55 may be a separate device from the loom and placed in suitable position to enable the weaver to readily supply the battery or hopper of the loom with filling carriers in the 60 manner hereinbefore pointed out.

What is claimed is:—

1. In a device of the character described, the combination of means for holding filling carriers having filling wound thereon, and a 65 filling end finder to find and hold the end

of the filling as the carriers and filling finder are relatively moved in a direction transversely to the longitudinal axis of the carriers.

2. In a device of the character described, 70 the combination of a frame for holding filling carriers for movement in a direction transversely of their longitudinal axes, and a filling end finder to act upon the filling on the carrier and find the end of the filling as 75 the carriers move transversely thereto.

3. In a device of the character described, 80 the combination of means for holding filling carriers having filling wound thereon, and a filling end finder to find and hold the end of the filling as the carriers and filling finder are relatively moved in a direction transversely to the longitudinal axis of the carriers, and means for causing the carriers to rotate to unwind the filling. 85

4. In a filling stand for looms, the combination of a filling carrier frame for holding filling carriers, a filling end finder, and means to relatively move the filling carrier frame and filling end finder transversely 90 that the latter may find and hold the filling ends as the frame and finder are so relatively moved.

5. In a filling stand for looms, the combination of means for holding a plurality of 95 filling carriers having filling wound thereon, a filling end finder to act upon the filling on the carriers while in said holding means, and means for relatively moving the filling carriers and finder that the latter may find 100 and hold the ends of the filling as the carriers and finder are relatively moved.

6. In a filling stand for looms, the combination of means for holding a filling carrier having filling wound thereon, a filling 105 end finder, and means for relatively moving the filling carrier and the filling end finder transversely of the carrier that the finder may act upon the filling to engage and hold the end thereof. 110

7. In a device of the character described, the combination of means for holding a filling carrier having filling wound thereon, a filling end finder, means for relatively moving the filling carrier and filling end finder 115 that the latter may act upon the filling, and means for rotating the filling carrier as the filling carrier and finder are so relatively moved.

8. In a device of the character described, 12 the combination of means for holding a plurality of filling carriers and a filling end finder, said carriers and finder being relatively movable in a direction transversely 12 of the longitudinal axes of the carriers to cause the filling end finder to find and hold the end of the filling and unwind it from the carrier during such relative transverse movement. 13

9. In a device of the character described, 13

- the combination of means for holding a filling carrier having filling wound thereon, operating devices for moving said means, mechanism for rotating the filling carrier in said means as it is moved, and means for engaging and holding the end of the filling as the carrier is moved by its holding means.
10. In a filling stand for looms, the combination of a supporting frame, a filling carrier frame slidably mounted in said supporting frame and adapted to sustain filling carriers having filling wound thereon, a filling end finder adapted to engage the filling on the filling carriers as the latter are moved by said carrier frame, and means for rotating the filling carriers.
11. In a device of the character described, the combination of a supporting frame, means for holding filling carriers, a filling end finder, and means for operating the filling carrier holding means to move the filling carriers therein past the filling end finder and present the filling carriers in position to be removed from said filling carrier holding means with the ends of the filling extending from the filling carriers.
12. In a filling stand for looms, the combination of a filling carrier frame for holding filling carriers having filling wound thereon, a hopper, a chute leading from the hopper to deliver filling carriers to said frame, means for moving the filling carrier frame, and a filling end finder to act upon and find the end of the filling as the frame is moved.
13. In a filling stand for looms, the combination of a frame for holding filling carriers having filling wound thereon, a guide for said frame, a filling end finder projecting into the path of the filling as the carriers are moved by said frame, and means for moving said frame to carry the filling carriers past the filling end finder that said filling carriers may be presented to the operative in convenient position for removal from said frame with the filling ends projecting from the carriers.
14. In a filling stand for looms, the combination of a frame for holding filling carriers having filling wound thereon, a guide for said frame, a filling finder projecting into the path of the filling as the carriers are moved by said frame, and means for moving said frame to carry the filling carriers past the filling end finder that said filling carriers may be presented to the operative in convenient position for removal from said frame with the filling ends projecting from the carriers.
15. In a device of the character described, the combination of means for moving said frame to carry the filling carriers past the filling end finder that said filling carriers may be presented to the operative in convenient position for removal from said frame with the filling ends projecting from the carriers, and means for engaging the filling on the carriers as they are moved past the filling end finder to rotate the filling carriers.
16. In a device of the character described, the combination of means for holding a plurality of filling carriers for surface movement transversely of their longitudinal axes, a brush for acting upon the filling during such surface movement to find the end of the filling and cause the same to be unwound from the carrier during such surface movement.
17. In a filling stand for looms, the combination of a frame having seats to receive the base and tip portions of filling carriers, a filling end finder comprising a brush to act upon the filling, means for relatively moving the frame and brush to enable the latter to find the end of the filling, and means for rotating the filling carriers in said frame in a direction opposite to the direction of filling wind.
18. In a filling stand for looms, the combination of means for supporting filling carriers having filling wound thereon, a filling end finder to act upon the body of filling, devices also acting upon the body of filling to rotate the filling carriers, and means for relatively moving the filling carriers and said finder and rotating devices.
19. In a filling stand for looms, the combination of a filling carrier frame for supporting filling carriers having filling wound thereon, a filling end finder to act upon the body of filling to find the end thereof, and treadle means for relatively moving the filling carrier frame and filling end finder to cause the latter to find and hold the filling ends.
- In testimony whereof, I have signed my name to this specification, in the presence of two subscribing witnesses.
